UNITED STATES PATENT OFFICE.

EDWIN T. GREENFIELD, OF KIAMESHA, NEW YORK.

TUBING.

No. 919,001.

Specification of Letters Patent.

Patented April 20, 1909.

Application filed June 11, 1906. Serial No. 321,187.

To all whom it may concern:

Be it known that I, EDWIN T. GREENFIELD, a citizen of the United States, residing at Kiamesha, in the county of Sullivan 5 and State of New York, have invented certain new and useful Improvements in Tubing, of which the following is a specification.

This invention relates to tubing of the 10 type consisting of successive spirally-formed convolutions of metal strip, the edge of each convolution overlapping that of the next adjacent one.

The object of the invention is to provide 15 an improved tubing of this character and one which, though useful in many and widely different ways, is of particular utility as piping for a fluid under pressure, as for instance, steam or compressed air. Such 20 spirally-formed tubing has been adapted for this purpose heretofore by the provision of a gasket of compressible material between the overlapping portions of adjacent spirals in order to preclude leakage of the air or 25 steam at the joints between the spirals. In all of these tubings, the strip from which the tube is formed has been curved laterally to provide for an interlock between adjacent 30 spirals and flexibility of the tubing has been obtained by permitting each spiral to move relatively to the adjacent spiral, until the 35 interlocking parts of the two spiral came into engagement. I have found that the best results are obtained, particularly where 40 the tubing is used as piping for steam or compressed air, when the maximum flexure of the tubing is somewhat limited since excessive bending is apt to open seams at the joints between the spirals through which the 45 fluid may escape. My invention contemplates the provision of means for precluding such excessive flexing of the tubing and, in the preferred form of my invention, I accomplish this by the employment of a tube 50 concentric with and inclosing the tube carrying the fluid and so constructed that it cannot be bent more than a predetermined amount, which amount is such that in making the maximum bend, the spirals of the 55 inner tube will not be moved relatively so much as to open seams and permit leakage between them. The strip from which the inner tube is formed is given a peculiar transverse curvature and a plurality of gas- 60 kets are spirally formed therewith in pockets arranged to receive them so that leakage of

air or steam from the tube is reduced to a minimum whether the tube be straight or curved.

I will describe my invention in connection 60 with the accompanying drawings which show the preferred embodiment thereof and in which—

Figure 1 is a sectional elevation of a piece 65 of the tubing bent to the arc of a circle and Fig. 2 is an enlarged sectional view of a portion thereof.

Referring to these drawings, the tubing consists of two concentric tubes each 70 consisting of successive spirals of a metallic strip. The strip for each tube is curved transversely in any suitable manner, as for instance by means of the mechanism shown in Patent Number 630,503 heretofore granted to me. The strip A for the inner tube may 75 have a main portion a and on either side thereof a flange a' and a'' ; beyond the flange a' is an outwardly curved portion a^3 and beyond the flange a'' is a depressed portion a^4 ; a flange a^5 and an inwardly curved portion a^6 . Such strip is spirally-formed into a tube with each spiral overlapping a portion of the next adjacent spiral and compressible gaskets c and c' are simultaneously wound thereon, the gasket c lying between 85 the outwardly curved portion a^3 of one spiral and the depressed portion a^4 of the next and the gasket c' between the inwardly curved portion a^6 of one spiral and the main portion a of the next. The strip is 90 wound very tightly to form the tube, the gaskets being compressed by the parts between which they are confined, so that practically no leakage of air or steam from the tube would occur. Ample flexibility is provided as each spiral can move relatively to the adjacent one. Concentric with and inclosing this tube is an outer tube formed 95 of a strip B. This strip has a body portion b , flanges b' and b'' at the sides thereof and, 100 beyond the flange b' , a depressed portion b^3 and flange b^4 . The strip is formed spirally with each spiral overlapping a portion of the adjacent one, the edge of flange b' of one spiral bearing on the depressed portion b^3 of the next. This tube is also flexible as 105 the edge of each flange b' can move over the portion b^3 and such movement of the spirals relatively is limited by the engagement of the flanges b' and b^4 . The distance 110 between the flanges b' and b^4 when the tube is straight, is less than the distance between

the flanges a' and a^5 of the tube A so that when the piping as a whole is bent the flanges b' and b^4 of the spirals of the outer tube engage and prevent further flexing 5 while the flanges a' and a^5 of the spirals of the inner tube are still separated. This condition is illustrated in Fig. 1 in which the tube is shown as bent to the maximum flexure permissible. It will be seen that the interlocking flanges of the outer tube are in contact and therefore further relative movement is precluded while the interlocking flanges of the inner tube are out of contact.

Having described my invention what I 10 claim as new and desire to secure by Letters Patent is:

A tubing comprising the combination of a water-tight tube consisting of a series of metallic, interlocking, relatively movable

spirals having a gasket between the adjacent 20 spirals thereof and a second tube inclosing said first-named tube and also consisting of a series of metallic, interlocking, relatively-movable spirals, said second tube being arranged to limit the flexure of the tubing in 25 the direction of its length by being so constructed that when the tubing is flexed in the direction of its length the interlocking parts on the outer tube come into engagement to preclude further flexure while the interlocking parts of the inner tube are separated, substantially as set forth.

This specification signed and witnessed this 8th day of June, 1906.

EDWIN T. GREENFIELD.
